COLLAPSIBLE PACKAGE

Jack W. Simmons, Tallahassee, Fla.

Application February 28, 1936, Serial No. 66,274

2 Claims. (Cl. 217—47)

This invention relates to the art of collapsible packages, such as knockdown crates, boxes, etc., adapted for use as shipping containers for fruit and the like, particularly citrus fruits, especially grapefruit and oranges.

In the development of the art of loose cooperage the wire bound wooden crate or box has attained great popularity and wide commercial use as a shipping package or container. Various types of such packages have been produced, and by far the majority of such packages when filled require machine handling for lidding operations and for proper tying of the wire binding straps.

Prior to the advent of this invention the practice in this art has been, in the case of wire bound packages, to apply the lid after filling and then to tie together the loose ends of the wire strap elements carried by, respectively, the unit consisting of the bottom and sides, and the unit comprising the top. In those instances where a constricting central support is a necessity such practice precludes the possibility of uniform tying operations at the ends and center, due to the central upward bulge of the lid which must be present in a properly filled package, as will be understood by those skilled in the art.

An object of my invention is the provision of a loose cooperage wire bound package having bottom and side wall portions operatively connected by attached flexible binding elements of uniform length which extend entirely around the top, bottom and side walls as continuous elements wherein the ends are tied or suitably united at the time the bottom and side wall portions are assembled, and prior to the placing of end and partition panels and the application of a lid.

Another object is the provision of a knockdown package comprising a collapsible blank formed of a bottom and side wall portions associated in loosely hinged relation by flexible binding elements attached thereto and extending entirely therearound across the tops of the wall portions as pre-tied continuous elements.

Another object is the provision in such a package of a novel lid structure and method of assembling.

A still further object is the provision in a package of such character of separately applicable end and/or partition panel means having interlocking engagement with prefixed binding wires carried by the package body and extending across its top. Other objects will be apparent from the description to those skilled in the art.

The present disclosure constitutes a practical embodiment by which my invention is reduced to

practice. It is to be understood that the structural details of this disclosure are capable of variation as desired so long as they remain consistent with the scope of the invention as claimed.

Figure 1 of the drawings is a perspective view of the partially opened blank of the invention, comprising the bottom and side wall portions with prefixed binding wires.

Figure 2 is a top face perspective view of a lid employed in the package.

Figure 3 is a perspective view of an end panel, its assembled position being shown in dotted lines in Figure 1.

Figure 4 is a top plan view of the operatively assembled package with lid removed.

Figure 5 is an end elevation of the package as folded prior to use.

Figure 6 is a vertical longitudinal section through the complete package as service assembled.

Figure 7 is a horizontal section taken on the line 7—7 of Figure 6.

Figure 8 is a vertical section taken on the line 8—8 of Figure 7.

Figure 9 is a side elevation illustrating the method of applying the lid.

Figure 10 is a fragmentary end elevation illustrating a lid securing detail.

As disclosed, the package comprises a bottom portion or section B made of two or more spaced slats 11 arranged side by side and connected together at each end by a bottom end cleat member 12 suitably secured to the slats and overlying their inner faces, the cleat ends terminating flush with the outer side edges of the slats. In center partition packages an intermediate cleat 13 is provided, it being similar to the end cleats, similarly attached, and parallel thereto intermediate the ends of the bottom. The cleats are provided each with a longitudinal groove, 12' and 13' respectively, opening to their upper faces.

Associated with the bottom B are two opposite side wall sections W, each being formed of two or more slats 14 spaced apart and connected together at their ends by wall cleat members 15 attached to and overlying the inner faces of the slats, with their ends terminating flush with the outer side edges of the wall slats. In center partition packages each wall section is provided with an intermediate cleat 16 similar to the end cleats and parallel thereto. The cleats are provided each with a longitudinal groove, 15' and 16' respectively, opening to their inner faces.

The bottom and the side walls are permanently connected in loosely hinged relation by

means of flexible binding elements, here shown as binding wire straps. These elements 17 have their ends tied or otherwise joined so as to provide continuous bands that extend entirely around the package and across its top, they being securely attached to the walls and bottom. As shown best in Figures 4, 6 and 7, the wire 17 at each end is so positioned that it overlies approximately the longitudinal center of that portion of each of the cleats 12 and 15 which lies between the cleat groove and the adjacent end of the wall or bottom. Where the package length necessitates central support an intermediate binding element 17' is provided, and if used in conjunction with intermediate wall cleats, such as 16, it is arranged to overlie the cleats at one or the other side of the cleat groove.

The flexible binding elements 17 being continuous bands provide means whereby the bottom and wall sections are permanently connected in a loose hinged relation, forming a foldable blank which may be collapsed to one or the other side of the bottom to lie substantially flat as shown in Figure 5, with the separable lid and the end and partition panels nested between the folds.

With the blank opened to upright position the binding elements 17, 17', extend across the open top with only sufficient slack to take up the lateral expansion resulting when the package is filled. When opened to service position the side walls assume the perpendicular with respect to the bottom. End panels 18 are provided, being of proper dimensions to seat in the grooves of the end cleats on the walls and bottom. These panels are inserted in the wall cleat grooves and are pushed down in place, their bottom edge portions seating in the grooves 12' of the bottom end cleats. Each panel 18 has attached to its outer face inwardly of each side edge a vertical guide cleat 19 which abuts the adjacent wall cleat 15 and the bottom cleat 12. Each end panel cleat 19 has its upper end flush with the upper edge of the panel and has a thickness substantially equal the width of the adjacent abutting area of the bottom and wall cleats, so that when the end panels are in place the constricting force of the end binding elements or wires 17 occurs in the plane of the cleats 19, as will be evident from an inspection of Figures 6 and 7, being transmitted through the cleats to the end panels.

In center partition packages a center partition panel 20 is inserted in the grooves of the intermediate wall cleats 16 and pushed down to seat its lower edge in the seating groove of the bottom intermediate cleat 13.

When the panels have been positioned the package is filled in the usual manner and a lid member 21 is applied over the top. In the present disclosure the lid member comprises a rectangular section dimensioned to cover the package top and provided with means having interlocking engagement with the binding elements whereby to secure the lid in closed position. As shown, such means comprises a keeper 22 in the form of a cleat rigidly attached to the upper face of the top at one end and having its side edge at

the lid end cut on a bevel as at 23, the opposite side edge of the cleat being longitudinally undercut as at 24 to take over and house the adjacent wire bending element 17 when the lid is applied.

At its other end the lid member 21 is provided with an attached reinforcing cleat 25 through which is secured a pair of flexible bails 26, preferably formed of wire, providing tongues arranged to be flexed under the adjacent end wire strap 17 and bent back thereover to fasten the lid in place. As shown in Figure 9, the lid 21 is positioned by sliding its bevelled keeper at a downward angle under the binding wire 17 at one end and then pulling the lid forward to cause the keeper to engage over the wire which wedges in the keeper undercut, seating as shown in Figure 6. The flexible bails 26 are then inserted beneath the binding wire 17 at the opposite end and bent up and back over the wire to draw the lid down in place with an interlocked engagement with the binding wires at each end. The extent of the bails 26, their flexible nature, and the flexibility of the binding wires 17 enable the lid to be secured in place even though considerably bowed by the package contents.

An important feature of the invention resides in the fact that the lid overlies the central binding wire 17' when this is used, so that the presence of this binder does not interfere with application of the lid. Also, such an arrangement permits the use of binding wires of equal length as the central binding wire does not have to compensate itself to lid bulge. An added advantage is that the central binding wire 17' provides a support beneath the lid at its center and thus eliminates the possibility of damage to the package contents through too great a lid pressure in application or from sudden strains in transportation.

I claim:

1. A sectional collapsible package polygonal in cross section, one section comprising a lid, endless band flexible binding elements permanently attached to and connecting all said sections except the lid at the ends of the package, an endless band flexible binding element connecting all said sections except the lid intermediate the ends of the package, and said lid being detachably engageable beneath said binding elements at the package ends and overlying said intermediate binding element and directly supported thereby.

2. A sectional collapsible package polygonal in cross section comprising in combination, a bottom section, wall sections, panels transversely positioned between and engageable detachably with said sections, endless band flexible binding elements connecting said sections in hinged relation and extending transversely across the tops of said wall sections at each end of the package, a lid section, a cleat fixed to one end of said lid section and undercut for interlocking engagement with one of said binding elements, and fastener means at the other end of said lid section detachably engageable with said binding element at the other end of the package.

JACK W. SIMMONS.
